UNITED STATES PATENT OFFICE.

FAY A. YEAGER, OF MUSKEGON, MICHIGAN.

WINDOW CONSTRUCTION.

Application filed March 14, 1922. Serial No. 543,606.

To all whom it may concern:

Be it known that I, FAY A. YEAGER, a citizen of the United States of America, residing at Muskegon, in the county of Muskegon and State of Michigan, have invented certain new and useful Improvements in Window Construction; and I do hereby declare the following to be a full, clear, and exact description of the invention, such as 10 will enable others skilled in the art to which it appertains to make and use the same.

This invention relates to a window construction adapted to be placed in a window opening in a house or the like, in which 15 either sections of glass or screen may be detachably secured, the same being readily removable for interchanging at different seasons of the year, or at any other times when desired. It is an object and purpose of the 20 invention to construct a frame in which said glass or screen may be detachably held, the frame being made entirely from sheet metal at a low cost, and the means used for detachably securing the glass or screen sections 25 being simple, economical to make and sure and positive in action. Other objects and purposes, relating to a practical, efficient, and durable window frame construction, will appear as understanding of the 30 invention is had from the following description, taken in connection with the accompanying drawings, in which,

Fig. 1 is a front elevation of the window construction, parts being broken away and 35 in section to better disclose the construction.

Fig. 2 is an end view of the window frame.

Fig. 3 is a transverse section substantially on the plane of line 3—3, of Fig. 1.

Fig. 4 is a fragmentary side view and section showing the means used for detachably securing the screen or glass sections or panels in place in the frame.

Fig. 5 is a fragmentary perspective view 45 illustrating the connection of the cross members of the frame with the intermediate vertical member thereof.

Fig. 6 is a fragmentary perspective view showing the corner construction of the frame.

Fig. 7 is an elevation of the screen panels used, and

Fig. 8 is a like view of the glass panels used.

Like reference characters refer to like parts in the different figures of the drawings.

The outer frame of the window construction is rectangular in shape, the sides including parts 1 at each end being bent at right angles for a short distance to make sections 2 in each of which a short slot 3 is cut. The frame members are of angle formation, a flange 4 being integral with and extending inwardly from the side 1 and, similarly flanges 5 extend inwardly from the sections 2 and under the ends of the flanges 4 which are raised a distance equal to the thickness of the flange 5 so that flanges 4 and 5 lie in the same plane. Such raised portions are shown at 6.

The upper and lower cross members of the frame are also of angle formation, having flanges 7 and 8 disposed at right angles to each other, each being pressed inwardly at the ends, as indicated at 7^a and 8^a so as to 70 pass within the sections 2 and flanges 5 with the main portions of the flanges 7 and 8 in the same planes therewith. Each of the parts 7^a has an opening 9 therein designed to come into conjunction with the openings made by slots 3 when the frame members are 75 assembled. The frame is adapted to be placed in an opening, the sides of which are made by vertical casing members 10 and the upper and lower ends by casing members 11, screws 12 passing through openings 9 and 80 slots 3 and into the members 11 adjacent each corner of the frame. The slots at 3 permit a limited range of adjustment for 85 variations in sizes of windows, the openings not all being of exact size.

A vertical bar divides the frame substantially midway between its sides. This bar is made from sheet metal bent longitudinally at its middle to make two contacting portions 13, each being bent outwardly to form a flange 14, the flanges extending in opposite directions. At its ends the metal is formed into sleeves 15 open at one end, a slot 16 being cut through and lengthwise of each sleeve at its outer side. In each sleeve a bolt 17 is slidably mounted, having an operating pin 18 connected thereto and extending through the slot 16 in the sleeve with which it is associated. These bolts are 100 adapted to pass through openings in the flanges 7 and into sockets made in the casing members 11, as shown in Fig. 1, to thereby secure the vertical division member in place in the frame with its flanges 14 lying, at their ends against the flanges 8 of the 105 end members of the frame.

Substantially midway between the ends of the central vertical bar a headed pin 19 is permanently secured to each flange 14. Two cross bars are designed to be placed 6 between the central bar and the sides of the frame, each being formed from a flat piece of metal bent longitudinally at its middle back upon itself making a tongue 20 of double thickness, with oppositely extending 10 flanges 21 bent therefrom, and at one end being formed with a sleeve 22 having a longitudinal slot 23 in its outer side in which a bolt 24 is slidably mounted, it having an operating pin 25 projecting through the 15 slot 23. This bolt with the slidable mounting thereof is identical with bolt 17 and its mount and is designed to pass through an opening in the part 1 of the side bars of the frame and into suitable sockets in the 20 casing member 10. The inner ends of the cross bars thus made are partly cut away and slotted, as indicated at 26 for engagement with the headed pins 19, the disconnected parts being shown in Fig. 5 in position 25 for ready connection when desired. In fact it is very easy to connect or disconnect all of the intermediate frame bars from the outer frame without use of tools, the assembly being very easily attained, as is obvious. 30

The frame as made is adapted to receive glass or screen panels in the four open spaces in the frame. The screen section 26 is placed in a frame of metal having sides 35 27 and upper and lower ends 28, the frame being of a size such that it freely enters between the sides 1 and part 13 and between the ends 7 and the part 20, lying against the flanges 4, 14 and 21. Headed pins 29 40 are attached to and extend from the sides 1 and the parts 13 on which wedging locking members are slidably and detachably mounted. These locking members are made from sheet metal including a plate 30 from 45 which a bottom 31 is turned at right angles while an end 32 is also turned at right angles at one end of the plate 30. An inclined slot 33 is cut in the plate 30, at one end being enlarged, as indicated at 34 for the passage 50 of the heads of pins 29 in applying the locking members thereto. By moving the locking members in one direction, the bases 31 thereof may be wedged against the sides 27 of the screen panels, thus serving to securely hold them in position. On movement in the opposite direction, the panels are released, and if desired may be removed on removal of the locking members, or one of them for each panel, it being obvious that 55 the screen panels may thus be placed in the main frame and left as long as desired, being removable whenever desired.

In case the frame is to be equipped with glass panels, in place of the screen panels 60 the same are constructed as shown in Fig.

8, the rectangular section 35 of glass being finished at its edges with border strips 36, preferably of rubber. The glass panels are easily substituted for the screen panels one replacing the other, as is clear. 70

From the foregoing it is evident that a very simple and economically constructed window frame construction is provided adapted for use at all seasons of the year, obviating the placing of an additional screen construction within the window in the summer time, and when once secured in a window opening being left there permanently, the screen and glass panels being interchanged at different seasons. All of 75 the frame may be filled with either the screen or the glass panels, or partly filled with each. The frame may be adjusted to the window opening and permanently secured after once adjusted. The sheet metal construction is made easily with proper dies and at low cost. Various modifications in the detail of construction may be resorted to without departing from the invention which is defined in the appended claims and I consider my invention to include all such modifications as come 80 within the scope of the said claims. 85

I claim:

1. A construction of the class described comprising a rectangular frame having parallel sides and ends of angle cross section, each side and end having an inwardly extending flange, division members dividing the space within the frame into substantially equal sections, said division members having oppositely extending flanges lying in substantially the same plane with the flanges of the sides and ends of the frame, means at the ends of the division members for detachably connecting the same to the frame and to each other, movably mounted locking devices mounted on the sides of the frame and certain of the division members over said flanges whereby members of glass or screen may be secured in the frame against said flanges, or readily removed therefrom. 100

2. A construction of the class described comprising a rectangular frame having parallel sides and ends of angle cross section, each side and end having an inwardly extending flange, division members of T-shaped cross section dividing the space in the frame into substantially equal sections, one of said division members lying between and paralleling the sides of the frame and detachably connected at its ends therewith, and others of the division members lying between the sides of the frame and the first division member, means for detachably connecting the last division members to the first division member and the sides of the frame at the ends thereof, said division members having flanges lying in substantially the 110 115 120 125 130

- same plane with the flanges of the sides and ends of the frame, and movably and detachably mounted locking members on the sides of the frame and each side of the first division member mounted over the flanges thereof for detachably securing filling members in said sections of the frame against the said flanges of the frame and division members.
- 10 3. A construction of the class described, comprising an open frame having sides and ends, means permitting the adjusting of the sides of the frame limited distances toward or away from each other, division members 15 dividing the space within the frame into substantially equal sections, and means adjustably mounted on the frame and certain of the division members for detachably securing panels of glass or screen within said 20 sections of the frame, substantially as described.
4. In a construction of the class described, in combination with a window casing of rectangular shape having sides and upper and lower ends, a frame located within said opening comprising end members and side members having end portions turned toward and overlapping the ends of the end members, screws passing through said end portions of the side members and the ends of the end members of the frame into the upper and lower ends of the window casing, vertical and horizontal division members dividing the space within the frame into sections, said division members having detachable connection to the frame and to each other, and means on the sides of the frame and the vertical division member for detachably locking glass or screen filling members in said open sections of the frame.
5. A construction containing the elements in combination as defined in claim 4, said ends of the end members of the frame being longitudinally slotted for short distances for the passage of the said screws therethrough.
6. In a construction of the class described, an open rectangular frame having sides and ends of angle cross section with flanges projecting inwardly from each side and end of the frame, a division member of T-shaped cross section paralleling the sides of the frame and located substantially midway between the same, means at the ends of said division member for detachably connecting the same to the ends of the frame, two cross division members also of T-shaped cross section located in alignment between the sides of the frame and the first division member substantially midway between the ends of the frame, means at the ends of the cross division members for detachably connecting the same to said first division member and the sides of the frame, said flanges of the frame, and flanges of the division members serving as a backing for filling members placed thereagainst, and means movably mounted on the frame and the division members for detachably locking the filling members in place.

In testimony whereof I affix my signature.

FAY A. YEAGER.
